UNITED STATES PATENT OFFICE

160,538

CABINET FOR A RADIO RECEIVER

Carl Reynolds, Jr., Birmingham, Mich., assignor
to Avco Manufacturing Corporation, Cincinnati,
Ohio, a corporation of Delaware

Application April 20, 1950, Serial No. 9,350

Term of patent 7 years

(Cl. D56—4)

To all whom it may concern:

Be it known that I, Carl Reynolds, Jr., a citizen of the United States, residing at Birmingham, Michigan, in the county of Oakland, have invented a new, original, and ornamental Design for a Cabinet for a Radio Receiver, of which the following is a specification, reference being had to the accompanying drawing, forming a part thereof.

In the drawing, the single figure is a perspective view of the front, top, and right side panels of a cabinet for a radio receiver showing my new design. The opposite side of the cabinet is like the side shown, and the back is plain.

I claim:

The ornamental design for a cabinet for a radio receiver, as shown and described.

CARL REYNOLDS, JR.
